Design No. 2,544, dated January 8, 1867.

DESIGN FOR A MEDAL.

The Schedule referred to in these Letters Patent and making part of the same.

TO ALL WHOM IT MAY CONCERN:

Be it known that I, DAVID R. HITCHCOCK, of the town of Newton, in the county of Middlesex, and State of Massachusetts, have invented or produced a new and original design for an Impression or Ornament, of which the following is a full, clear, and exact description, reference being had to the accompanying drawings making part of this specification.

Figure 2 represents the obverse of the medal, with the words, "I will never do anything which my mother would not approve."

Figure 1 represents the reverse, with the words, "My mother's charm," the words on each face being surrounded with the present or any other similar or appropriate configurations.

What I claim as my design, and desire to secure by Letters Patent, is—

The embodiment of the words above written upon the obverse and reverse faces of a medal or charm, substantially as described.
